WALL

Clements Batcheller, Glens Falls, and Frederick Heft, Troy, N. Y., assignors to Allegheny Ludlum Steel Corporation, a corporation of Pennsylvania

Application March 4, 1937, Serial No. 129,002

8 Claims. (Cl. 72—38)

Our invention relates to walls and particularly to blocks of a novel type which, in connection with other elements, are adapted to be quickly assembled in precise aligned and spaced relation to form a wall structure.

Stainless steel is widely used for trim and decorative purposes in building construction, but large panels thereof, unless broken up by ornamental color effects or other means, are rather monotonous. Our invention, therefore, has to do with the construction of walls of which the major portion of the exposed surface is composed of stainless steel but which is formed of separate bricks or blocks having means simulating cement joints therebetween.

One of the objects of our invention is to provide a novel type of block having its exposed face enclosed in a cap of corrosion-resisting alloy steel, and provided with features adapting it to be easily combined by non-skilled help with anchoring, aligning and joint simulating means to form a perfect wall structure, and without the use of cement, mortar and the like. Another object is to provide a wall of this type which will be light in weight and substantially fireproof, and yet have practically the strength and solidity of a brick structure. A further object is to provide blocks of the character described which are easily "nail penetrable" whereby they may be secured together in the wall assembly by nailing.

With these objects in view, our invention includes the novel elements and the combinations and arrangements thereof described below and illustrated in the accompanying drawings in which—

Fig. 1 is a rear perspective view of one of the blocks or bricks used in forming our wall;

Fig. 2 is an end view of a block, partially in section;

Fig. 3 is a plan view of the metal blank used in forming the cap for the face of the block;

Fig. 4 is an end elevation view, partially in section, of part of a wall formed by our blocks;

Fig. 5 is a cross section of a combined block-aligning and horizontal joint-forming means;

Fig. 6 is a plan view of a joint-forming means used at a corner of the wall;

Fig. 7 is an elevation view of a vertical joint-forming means;

Fig. 8 is an end view of the joint-forming means shown in Fig. 7;

Fig. 9 is a perspective view, looking from the rear, of a corner block;

Fig. 10 is a rear view of a modified form of block;

Fig. 11 is an end view of the block shown in Fig. 10;

Fig. 12 is an end view of a modified block of the general type shown in Fig. 1;

Fig. 13 is an enlarged fragmentary top view of the block shown in Fig. 12;

Fig. 14 is a fragmentary perspective view of a wall showing a corner construction; and

Fig. 15 is a plan view showing parallel walls which are tied together in spaced relation.

Referring to the drawings and particularly to Figs. 1, 2, 3, 4 and 14, our wall 1 comprises a plurality of blocks 2 arranged in horizontal courses 3, 4, etc., preferably with staggered vertical joints between the blocks. While it is to be understood that our invention is not limited to any particular size of block, for purposes of illustration, it may be assumed that the block shown in perspective in Fig. 1 is approximately the size and shape of an ordinary pressed brick. Except where it is desirable to seal the wall against the passage of gas or liquids, it is to be understood that the blocks are laid without cement and are secured together in assembled wall relation by means of anchors and by nailing the courses together. It is therefore desirable that the material of which the block is formed should be easily "nail-penetrable". It is also desirable that the wall be substantially fireproof and hence the material from which the blocks are formed should have the characteristics of nail penetrability without cracking or spalling, and also high resistance to heat.

The blocks are formed by a molding operation from a suitable plastic composition, and while it is to be understood that we are in no sense limited to the particular composition or the particular proportions of ingredients set forth, the following will be found to provide a very satisfactory block—

	Grams
Cellulose (waste pulp fibers)	750
Portland cement	750
Calcined magnesite	300
Bentonite	400
Diatomaceous earth	300
Waste asbestos (C fibers)	400
Water in a quantity sufficient to form a plastic mixture.	

This composition will form a hard product but one which has properties quite different from those of the ordinary cement asbestos products well known in the shingle and sheathing industry, and particularly, in that it is of comparatively

light weight (only about 48 to 50 pounds per cubic foot) and that it can be sawed, drilled, nailed and otherwise worked with about the same facility as hard wood.

5 The exposed faces of the blocks are enclosed in rectangular caps 5 of sheet metal, preferably thin-gauge, corrosion-resistant, alloy steel, which are formed from rectangular blanks 6 cut to the shape shown in Fig. 3. The longer edges are 10 slotted at spaced intervals, as shown at 7, to provide tongues 8 which are bent inwardly as shown in Fig. 2 and serve to anchor the steel caps to the face of the block. The notches formed by bending in the tongues also provide openings for 15 the egress of water from the cap during the molding of the block. The edges of the blank 6 are bent upwardly at right angles to the face of the plate along the dotted lines 9, 10, 11 and 12 of Fig. 3 to form upstanding flanges 13, as shown in Fig. 2, which fit over and partially enclose the top, bottom and sides of the block. The blocks 20 2 should be molded under substantial pressure and a very firm bond is then obtained between the plastic material forming the body of the block and the metal cap or facing 5.

The top and bottom of each block are provided with vertically-aligned, centrally-disposed channels 14 and 15 respectively, extending parallel to the face of the block. Preferably, also, these 30 channels are extended around the ends of the block, as shown at 16 and 17. The top and bottom of the block are also provided with the vertically-aligned channels, 18 and 19, and 20 and 21, which are positioned adjacent the ends of the block. These channels are of the same depth as the channels running parallel to the face of the block and extend from the back of the block to the centrally disposed channel. These last mentioned channels, 18, 19, 20 and 21, are at the 40 same distance from the ends of the block as the centrally disposed channels are from the face of the block.

In Fig. 9 we have shown a corner block having longitudinally extending grooves or channels 22 45 in the top and bottom thereof which are similar to the channels 14 and 15 in the block shown in Fig. 1. Here, however, both the face 23 of the corner block and one end 24 are enclosed in a metal cap 25 similar to the metal cap 5. Vertically aligned cross channels, 26 and 27, and 28 and 29, similar to the channels, 18 and 19, and 20 and 21, are provided and extend from the back of the block to the centrally disposed channels.

55 Referring particularly to Figs. 4, 5, 6, 7, 8, 9 and 14, a suitable foundation 30, such for example as a cast or rolled section, is provided for our wall. The first horizontal layer of blocks is secured thereto by means of bolts or cap screws 60 31 which are threaded into the base 30 as shown at 32. The base or foundation 30 is provided along the top with a centrally-disposed, longitudinally-extending boss 33 which is adapted closely to interfit with the grooves or channels 15 in the bottoms of the first course of blocks. The height of the boss 33 is somewhat greater than the depth of the channels 15 so that the bottoms of the blocks at the front and back are spaced above the general level of the base 30 to permit the insertion therebetween of strips 34 and 35. These strips may be of the same material as that of which the blocks are formed and are positioned in the spaces between the bottoms of the blocks and the top of the foundation to simulate cement joints. The exposed edges of these

strips may be appropriately colored to simulate colored mortar. After the first course of blocks is secured in place, anchoring strips 37 are positioned in the channels 14 in the tops of the first course of blocks. These anchoring strips may be 5 made of the same material as the blocks and of a width designed to interfit closely with the channels 14 in the top of the first course and the channels 15 in the bottom of the second course of blocks. The vertical thickness of these strips 10 is substantially equal to twice the depth of the channels in the blocks plus the thickness of the joint simulating strips 34 and 35. Where the anchoring strips 37 overlie the bolts or cap screws 31, they may be recessed to receive the heads or 15 nuts 38 therein. Vertical cement joints between the blocks in each course are simulated by the plates 39 which may be of the same material as the blocks and anchoring strips. These plates are of the same thickness as the strips 34 and 35 20 and of the same height as the blocks. They are provided at the top and bottom central portions with notches 40 and 41 adapted to interfit closely with the anchoring strips 37. In Fig. 7, the dot-dash line 42 is the geometrical center of the plate 25 39 and, it will be observed that the notches 40 and 41 are not precisely centered on this line. The length of the plates 29 is less than the width of the blocks so that the edges of the plates when positioned in the wall set somewhat back from 30 the metal face. The purpose of the asymmetrical disposition of the notches 40 and 41 with respect to the center of the plate is to permit the wall builder to have a choice of two distances to which the vertical joints may be set back from 35 the face of the wall. The vertical edges 43 and 44 may be colored as shown at 45 in the same manner as described for the edges of the strips simulating the horizontal joints. Except for the horizontal joint between the first horizontal course and the foundation, the anchoring strips and the horizontal, joint-simulating strips may 40 be formed in one unit 46, as shown in Fig. 5.

At the corners of the wall, corner blocks of the type shown in Fig. 9 are employed and it will be 45 apparent from a consideration of the block shown in Fig. 9 and the wall shown in Fig. 14 that only one type of corner block is necessary because the top and bottom surfaces of the blocks are identical and they may be used either side up. The anchoring strips 39 extend into the channels 22, 26 and 27 in the corner blocks and secure them in perfectly aligned relation with the other courses. The horizontal, joint-simulating strips at the corners are preferably made angular, as shown at 55 50 in Fig. 6. After each course is laid, the next succeeding course, including the anchoring strips, may be readily nailed thereto so that a very solid wall structure is obtained.

The vertically aligned cross channels 18 and 19, and 20 and 21 also function to receive H-shaped anchoring elements 47 for securing together parallel walls 48 and 49 as shown in Fig. 15.

The channels 16 and 17 in the ends of the block are for the purpose of permitting the blocks to be 65 laid vertically as well as horizontally and yet cooperate with the anchoring strips 39.

Where it is desirable to seal the wall against the passage of gasses or liquids, we provide the blocks with additional small grooves 51 extending 70 entirely around the rear portion thereof as shown in Figs. 12 and 13. These grooves may be filled with a suitable sealing material.

While for most uses our blocks will probably be made of the general size and shape of pressed 75

bricks, it is to be understood that the invention is not limited in this respect. For example, in Figs. 10 and 11 we have shown a block 52 having a square face enclosed in a metal cap 53 and provided with a centrally disposed channel 54 extending entirely around the block and which is adapted to interfit with the anchoring strips 37. In blocks of large size, such for example as those shown in Figs. 10 and 11, portions 55 may be 10 made hollow to save material and also to lighten the block.

From the foregoing it will be apparent that skilled labor is not necessary to construct our wall. The blocks are automatically positioned 15 and maintained in perfectly aligned relation by means of the anchoring strips, and because the material of which the blocks, and the anchoring and joint-simulating strips are formed, permits them to be readily nailed together and also to be sawed and otherwise worked, a perfect and very 20 solid wall can be quickly constructed by anyone.

Half-bricks can be made for finishing the ends 25 of the wall, and by varying the thickness of the joints almost any space can be completely filled with our blocks.

Although substantially only the faces of our 30 blocks are covered with metal, walls made therefrom nevertheless appear to be made from solid metal blocks because the sheet metal facing extends around the edges of the face and far enough over the top, bottom and sides of the block so that its inner edges are concealed by the joint-simulating strips.

While we have described our invention in its 35 preferred embodiment, it is to be understood that the words which we have used are words of description rather than of limitation. Hence, changes within the purview of the appended claims may be made without departing from the 40 true scope and spirit of our invention in its broader aspects.

What we claim is:

1. A wall comprising a plurality of blocks provided with channels therein and arranged in horizontal courses, means interfitting said channels in a plurality of blocks in each of two vertically adjacent courses for maintaining said blocks in aligned relation and said courses in vertically spaced relation, and means simulating cement 50 joints positioned between said courses.

2. In a wall, the combination with a plurality of blocks provided with channels therein and arranged in two, adjacent, horizontal courses, of an anchoring strip positioned between said courses 55 and cooperating in interfitting relation with said channels in a plurality of blocks in each of said courses to simulate a cement joint between said courses and to maintain said blocks in spaced aligned relation, and means cooperating in inter- 60 fitted relation with said strips to simulate vertical joints between said blocks and maintain them in horizontally spaced relation.

3. A building block having a front face and comprising a rectangular, prism-like body provided with a centrally disposed groove therein extending entirely around said body and parallel to said face and having oppositely disposed grooves in the top and bottom thereof and adjacent each end of said block extending from the 65 back thereof to said centrally disposed groove.

4. A building block comprising a rectangular, prism-like body having a front face and provided with a centrally disposed groove extending entirely around the body thereof parallel to said face, and having oppositely disposed grooves in the top 5 and bottom thereof and adjacent each end of said block extending from the back thereof to said centrally disposed groove; the distance of said opposite disposed grooves from the ends of said block being the same as the distance of the centrally disposed groove from the face of said block. 10

5. A wall comprising a plurality of rectangular blocks arranged in horizontal courses and provided in the top and bottom thereof with a longitudinally extending channel, anchoring strips 15 somewhat thicker than twice the depth of said channels and positioned therein between adjacent horizontal courses of said blocks, whereby said courses are vertically spaced from each other, strips simulating cement joints positioned between said courses, and spacing means cooperating with said anchoring strips and positioned between adjacent blocks in said horizontal courses to simulate cement joints. 20

6. A wall comprising a plurality of rectangular blocks arranged in horizontal courses and provided on the top and bottom with aligned, longitudinally-extending, centrally disposed channels; anchoring strips positioned between said courses comprising central, comparatively thick portions 30 closely interfitting with said channels in the bottom of the course above and with said channels in the top of the course below, and comparatively thin side portions extending toward the face of said wall to simulate cement joints between said 35 courses, and spacing plates interfitting with the central portions of said anchoring strips between adjacent blocks in each of said courses to simulate vertical cement joints. 40

7. In a wall comprising a plurality of rectangular blocks arranged in horizontal courses and provided in the top and bottom with vertically-aligned channels extending parallel to the face of said wall; a corner construction comprising rectangular corner blocks provided in the top and bottom with vertically-aligned, angularly disposed channels extending parallel to the exposed sides and ends, respectively, of said blocks, anchoring strips somewhat thicker than twice the depth of said channels closely fitted therein between said corner blocks in adjacent horizontal courses whereby said corner blocks are maintained in vertically spaced and aligned relation, and plates simulating cement joints positioned in the spaces between said blocks and interfitting with said anchoring strips. 50 55

8. In a wall, the combination with a plurality of blocks provided with channels therein and arranged in two, adjacent, horizontal courses, of an anchoring strip positioned between said courses; said strip being provided with a central portion cooperating in interfitting relation with said channels in a plurality of blocks in each of said courses, and with a portion extending toward the face of said wall to simulate a cement joint between said courses. 60 65
